UNITED STATES PATENT OFFICE.

WILLIAM E. HINCHLIFF, OF ROCKFORD, ILLINOIS, ASSIGNOR TO BURSON MANUFACTURING COMPANY, OF ROCKFORD, ILLINOIS, A CORPORATION OF ILLINOIS.

HOSIERY.

1,262,668.

Specification of Letters Patent. Patented Apr. 16, 1918.

Application filed July 19, 1915. Serial No. 40,665.

To all whom it may concern:

Be it known that I, WILLIAM E. HINCHLIFF, a citizen of the United States, residing at Rockford, in the county of Winnebago and State of Illinois, have invented certain new and useful Improvements in Hosiery, of which the following is a specification.

This invention relates to improvements in knit hosiery, being more particularly applicable to ladies' stockings. The object of the invention is to produce a stocking which in service will be free from the objection technically known as "runs" or "ladders." It is a well known fact that the stitching of the hem at the upper end of the leg produces a weakening effect upon the loops of the fabric in the region of the stitching by reason of the hemming needle penetrating the loops, the result of which is that during usage when a hose supporter has been fastened to the hem, one or more of the loops will break usually at the hem, producing a "run" or "ladder," which sometimes extends down the leg nearly or quite to the ankle portion of the stocking. This fault is particularly inherent in stockings that are knitted from thread that has been processed in such a manner as to render its surface comparatively hard, sheer and smooth. My present invention is the result of an effort to obviate this defect in stockings of the general character referred to and consists, generally stated, in knitting the upper portion of the leg for a substantial distance, of a rough, unprocessed thread or yarn to receive the hose supporter, this rough or unprocessed yarn producing somewhat the effect of a fulled fabric, the rough yarns or threads of which engage each other with considerable friction, so that, even if a break occurs in one or two loops, such break or run will not extend down into the main leg portion that is knitted of hard, smooth or sheer thread. I find that the efficiency of the stocking to resist the formation of "runs" or "ladders" is enhanced if the same be provided with a relatively narrow hem, so narrow that the hose supporter will be fastened at a point below the line of the hem. To assist in a clear understanding of the invention, I have illustrated in the accompanying drawing a lady's stocking embodying my improvements, the figure being an elevational view of the stocking laid flat.

Referring to the drawing, 5 designates the foot portion and 6 the major leg portion, these parts being knitted of a comparatively hard, smooth processed thread with the exception of the heel, toe and under foot portions which are reinforced by unprocessed thread. At the point or line designated by 7, a thread of different character is introduced to the needles of the machine to form the upper leg portion 8, this thread having a rough or unprocessed yarn surface and, when dyed, producing a result somewhat similar to fulling. The upper part of the leg portion 8 is folded over and stitched along the line 9 to form a narrow hem 10, this hem, as previously stated, being so narrow that the point of fastening of the hose supporter will be below the stitching 9.

Owing to the character of yarn used in knitting the portion 8 of the leg, this portion is made more proof against "runs" especially where not weakened by a line or lines of stitching, as in a hem, below the point of fastening of the hose supporter, and if a "run" starts in the portion 8, it will not extend as far as the line 7 forming the junction of the smooth and rough threads. By making the hem 10 narrow, as described, the fabric is not weakened by stitching below the point of fastening of the hose supporter.

While I have described the invention as intended chiefly for use in connection with ladies' hosiery, it should be understood that the same is not limited thereto but may usefully be embodied in men's and children's hosiery to improve the wearing qualities thereof.

I claim:

A stocking of the character described having a lower leg portion knitted of smooth, sheer yarn, and the upper portion knitted of a relatively softer yarn by introducing the latter in the course of knitting so as not to break the continuity thereof, the upper knit portion having a narrow hem at its upper end of such width as practically to insure the point of fastening of the hose supporter below the line of said hem, whereby the pulling strain of the hose supporter is distributed divergently lengthwise with considerable uniformity to loops of equal strength, thereby preventing "runs" in the stocking.

WILLIAM E. HINCHLIFF.
